UNITED STATES PATENT OFFICE.

WILLIAM P. FRANCL, OF BROOKLYN, NEW YORK.

DRY PIPE FOR BOILERS.

1,261,729.

Specification of Letters Patent.

Patented Apr. 2, 1918.

Application filed July 10, 1916. Serial No. 108,314.

To all whom it may concern:

Be it known that I, WILLIAM P. FRANCL, a citizen of the United States, and a resident of Brooklyn, in the county of Kings and 5 State of New York, have invented certain new and useful Improvements in Dry Pipes for Boilers, of which the following is a specification.

This invention relates to a dry pipe for 10 boilers and the like. It is applicable also to exhaust mufflers of automobiles, vehicles or the like, as well as for many other purposes.

In the accompanying drawings Figure 1 represents a longitudinal section of the invention with the shell of a boiler; Fig. 2 shows a top plan view of some of the elements of Fig. 1; Fig. 3 is a section as on the line 3, 3 of Fig. 1; Fig. 4 represents a longitudinal section of a modification of the invention and Fig. 5 is an enlarged section as 20 on the line 5, 5 of Fig. 4.

Referring to Figs. 1 to 3 the invention, connected to the top shell of a boiler is shown to comprise an outer casing consisting of the 25 pair of members 10 and 11. The said members have respectively formed therein the longitudinal slots 14 and 15, and in this instance at the lower portions of said members. The said slots may be formed at the upper 30 portions of the members. An inner casing comprises the pair of members 20 and 21, having respectively formed therein the longitudinal slots 23 and 24, which in this instance are in the upper portions thereof. 35 Small openings 25 are formed in the lower portions of the members 20 and 21. The latter slots may be made in the lower portions of the members 10 and 11.

A T 30 connects the accompanying adjacent ends of the pair of members 10 and 11 as well as the accompanying ends of the members 20 and 21. Caps 32 are connected to the outer ends of the members 10, 20 and the members 11 and 21.

45 A nipple 33 is in threaded engagement with the T 30. A boiler shell 35 has connected thereto a fitting 36 for piping not shown, and the nipple 33 extends into said fitting 36. An annular duct 37 is formed between the outer casing comprising the members 10 and 11, and the inner casing comprising the members 20 and 21.

In the modification of the invention shown in Figs. 4 and 5, the dry pipe is connected 55 to the side shell 39 of a boiler. The outer casing of this modification comprises the

member 40 having the longitudinal slot 41 in this instance at the lower portion thereof. The inner casing comprises the member 42 with the longitudinal slot 43 at the upper 60 portion thereof. Small openings 44 are made in the inner casing 42. A cap 45 connects one end of said members 40 and 42 and a separator ring 46 is shown at the other end thereof. The member 42 is extended into 65 an opening 50 in the shell 39 of the boiler and may be threaded herein. A fitting 52 coaxial with the dry pipe is connected to the shell 39. An annular duct 53 is formed between the members 40 and 42. Hangers 55 70 extend from the upper wall of the boiler shell and support the dry pipe.

The operation of the invention depends upon the separation of the water in the steam by centrifugal force. In Figs. 1 to 3 the 75 steam enters the slots 14 and 15 of the outer casing, whirls in the annular ducts 37, and flows into the inner members 20, 21 through the slots 23 and 24 on its way out of the dry pipe and into the fitting 36. The whirling 80 of the steam separates the water therefrom by striking the sides of the outer members 10 and 11. From the latter the water is drained through the slots 14 and 15 and any water collected in the inner members 23 and 24 is 85 drained by means of the openings 25.

The operation for the modified form of the invention is similar to that already described. With the latter construction it can be made applicable as a muffler for the exhaust of an engine.

Having described my invention what I desire to secure by Letters Patent and claim is:

1. In a device of the character described 95 the combination of an outer casing comprising a pair of members, an inner casing concentric with the outer casing and comprising a pair of members, a T connecting the accompanying ends of said members, a cap 100 covering the outer ends of said members, each outer casing having a longitudinal slot in the lower portion thereof, each inner casing having a longitudinal slot in the upper portion thereof and openings in the lower 105 portion thereof.

2. In a device of the character described 110 the combination of a T, an inner casing and an outer casing concentric with each other extending from opposite sides of said T, caps for the outer ends of the casings, the inner and outer casings forming a duct

- between them, each outer casing having a longitudinal slot and each inner casing having a longitudinal slot, the slots positioned not to be in line with each other, said inner casings having openings in the lower portions thereof to drain a fluid from said inner casing, and means to connect the device to the inner surface of the shell of a boiler.
- 10 3. In a dry pipe the combination for an outer horizontal casing comprising a pair of members each with a longitudinal slot at the lower portion thereof, an inner casing concentric with the outer casing comprising a 15 pair of members, each of the latter mem-

bers having a longitudinal slot in its upper portion and a plurality of openings at the lower portion, a T connecting the adjoining ends of the outer and inner casings, caps at the outer ends of the casings, the inner and outer casings forming ducts between them and means to connect the dry pipe to the shell of a boiler.

Signed at the borough of Manhattan in the county of New York and State of New York this 30th day of June A. D. 1916.

WILLIAM P. FRANCL.
